UNITED STATES PATENT OFFICE.

THOMAS M. JERVEY, OF THE UNITED STATES ARMY, ABERDEEN PROVING GROUND, MARYLAND.

MACHINE-GUN UNIT.

Application filed January 13, 1926. Serial No. 81,079.

(GRANTED UNDER THE ACT OF MARCH 3, 1883; 22 STAT. L. 625.)

The invention described herein may be used by the Government, or any of its officers or employees in prosecution of work for the Government, or by any other person in the

United States, without payment to me of any royalty thereon, in accordance with the act of March 3, 1883.

This invention relates to a machine gun unit and in particular it has reference to a sear release mechanism applicable for synchronized guns mounted on aircraft.

The principal object of this invention is to provide a sear release mechanism for machine guns of the above specified type in which a lever is utilized to release the sear, and this lever is so mounted as to operate the sear more easily than existing types of releases while at the same time supplementing the action of the sear spring by normally tending to hold the sear engaged, thereby increasing the positive locking action of the sear and insuring semi-automatic operation of the gun.

To these and other ends, my invention consists in the construction, arrangement, and combination of elements, described hereinafter and pointed out in the claims forming a part of this specification.

A practical embodiment of my invention is illustrated in the accompanying drawings, wherein:

Fig. 1 is a transverse sectional view through a machine gun showing, in rear elevation, a bolt provided with a sear mechanism constructed in accordance with the invention;

Fig. 2 is a sectional view through the bolt on the line 2-2 of Fig. 1;

Fig. 3 is a longitudinal sectional view through the bolt;

Fig. 4 is a view in front elevation of the assembled sear and sear release mechanism;

Figs. 5, 6, 7 and 8 are detail views of the lever;

Figs. 9, 10, 11 and 12 are detail views of the sear;

Figs. 13 and 14 are detail views of the sear lever slide.

Referring to the drawings by numerals of reference:

There is shown at 5 the side plates of a machine gun between which reciprocates the bolt 6 carrying the firing pin 7 which is cocked in a well known manner by the lever

8. The pin is held in cocked position by a sear 9 slidable vertically in slots 6' cut in the rear face of the bolt and forced to pin-engaging position by a spring 10.

The sear is operated to release the firing pin by means of a transversely swinging lever 11 whose connection with the sear is preferably made by a slide 12 disposed in a groove 11' in the lever and having a cylindrical projection or stud 12' receivable in an aperture 9' in the sear. The lever is substantially in the form of a quadrant and in its normal position of rest when connected to the sear it is out of equilibrium, its fulcrum 13 being located at one side of the bolt so as to lie above and to one side of the center of gravity of the lever and thereby normally produce a force acting on the return stroke of the lever or when the lever is at rest, and supplementing the sear spring, for moving and holding the sear in firing pin engagement.

In order that the movement of the lever may be transmitted to the sear with as little effort as possible, the position of the groove 11' during operation is substantially along the horizontal plane so as to reduce to a minimum the resistance encountered in lifting the sear and furthermore the slide works in the outer portion of the groove to obtain a long lever arm. By thus converting circular into reciprocal motion the force required to operate the sear will be considerably less than that required with the slide mechanisms heretofore used and in addition by reason of the connection of the lever to the sear and its unbalanced state when in position of rest it will supplement the action of the sear spring in preventing disengagement of the sear.

The lower circumferential portion of the lever is reduced as at 14 for disposition in a slot or groove 15 in the bolt to prevent withdrawal of the lever after being assembled in the gun.

A conventional trigger motor includes the usual plunger 16 and a pawl 17 for rocking the lever and operates in a well known manner to synchronize the action of the gun and the airplane propeller.

While in the foregoing there has been illustrated and described such combination and arrangement of elements, as constitute the preferred embodiment of my invention,

it is nevertheless desired to emphasize the fact that interpretation of the invention should only be conclusive when made in the light of the subjoined claims.

I claim:

1. In a machine gun unit, a reciprocal breech bolt, a firing pin carried thereby and movable with respect thereto, a cocking lever for the pin, a centrally located sear, having an aperture, for holding the pin in cocked position, a lever of substantially quadrant form fulcrumed at one side of the bolt so as to place the lever in unstable equilibrium, said lever formed with a groove positioned during operation of the lever approximately in the horizontal plane, and a slide member disposed in the groove and having a projecting stud receivable in the aperture of the sear.
2. In a machine gun unit, a reciprocal breech bolt, a firing pin carried thereby and movable with respect thereto, a cocking lever for the pin, a centrally located sear, having an aperture, for holding the pin in cocked position, a lever fulcrumed at one side of the bolt and swinging across the center of the bolt, said lever formed with a groove positioned during operation of the lever approximately in the horizontal plane, and a slide member disposed in the groove and having a projecting stud receivable in the aperture of the sear.
3. In a machine gun unit, a reciprocal breech bolt, a firing pin carried thereby and movable with respect thereto, a cocking lever for the pin, a centrally located sear, having an aperture, for holding the pin in cocked position, a lever fulcrumed at one side of the bolt and swinging across the center of the bolt, said lever formed with a groove, and a slide member disposed in the groove and having a projecting stud receivable in the aperture of the sear.
4. In a machine gun unit, a reciprocal breech bolt, a firing pin carried thereby and movable with respect thereto, means for cocking the pin, a sliding sear for holding the pin in cocked position, a sear spring, a lever fulcrumed on the bolt to swing across the path of movement of the sear, and a connection between the lever and the sear whereby they move in unison.
5. In a machine gun unit, a reciprocal breech bolt, a firing pin carried thereby and movable with respect thereto, means for cocking the pin, a sliding sear for holding the pin in cocked position, a sear spring, a lever fulcrumed on the bolt, and a connection between the lever and the sear whereby they move in unison.
6. In a machine gun unit, a reciprocal breech bolt, a firing pin carried thereby and movable with respect thereto, means for cocking the pin, a sliding sear for holding the pin in cocked position, a sear spring for moving the sear to engage the pin, and means swingable transversely of the bolt for disengaging the sear, the normal position of said means being out of equilibrium so as to supplement the action of the sear spring.
7. In a machine gun unit, a reciprocal breech bolt, a firing pin carried thereby and movable with respect thereto, means for cocking the pin, a sliding sear for holding the pin in cocked position, a sear spring for moving the sear to engage the pin, and means swingable transversely of the bolt for disengaging the sear.
8. In a machine gun, a reciprocal breech bolt, a firing pin carried thereby and movable with respect thereto, means for cocking the pin, a sliding sear for holding the pin in cocked position, and sear actuating means mounted on the bolt for swinging movement.
9. In a machine gun, a reciprocal breech bolt, a firing pin carried thereby and movable with respect thereto, means for cocking the pin, a sliding sear for holding the pin in cocked position, and swinging means connected to the sear, the upward stroke of said means disengaging the sear and the downward stroke moving the sear into firing pin engagement.
10. The combination with a sear, of a lever fulcrumed adjacent the sear and swingable across the path of travel of the sear, and a sliding connection between the lever and sear.

THOMAS M. JERVEY.
